UNITED STATES PATENT OFFICE.

ERIK LANDER, OF OAKLAND, CALIFORNIA.

STEAMING APPLIANCE TO BE ATTACHED TO BATHTUBS.

Application filed June 25, 1925. Serial No. 39,479.

My invention is a steaming appliance to be attached to an ordinary bath tub by which a person may take a steam bath with only their head exposed outside of the steam chamber formed by the bath and the appliance.

An object of my invention is to provide a covering for a bath which may be attached to the rim of a bath and allow a person to sit in the bath with their head exposed above the covering and to leave their arms free below the bath to manipulate the faucets. In one form of my invention the covering is preferably formed of a rubberized fabric mounted at one end of the bath on a winding roller and positioned so that the covering may be extended and secured to the opposite end of the bath by buttons or eyelets and an opening is formed in the covering for the neck and an overlapping slit with buttons extends therefrom a sufficient distance to allow a person to button the covering securely around the neck.

In another form of my appliance the covering is preferably formed of one large sheet of rubberized fabric or the like, with a series of vacuum cups or other devices by which the person using the steam bath may secure the covering to the rim of the bath.

My invention will be more readily understood from the following description and drawings in which:

Figure 1 is a plan view of a bath as if taken in the direction of the arrow 1 of Figure 2 showing the covering appliance extended.

Figure 2 is a longitudinal section of Figure 1 on the line 2-2 showing the roller for supporting the covering sheet and the housing to enclose the roller.

Figure 3 is an alternative form in which the covering sheet is made in the form of a large loose covering fabric with a series of vacuum cups to be attached to the rim of the bath.

Figure 4 is an enlarged detail of the attachment of the vacuum cup to the covering sheet indicating the manner of attaching to the rim of the bath.

Referring particularly to Figures 1 and 2 the bath 1 is shown of a typical form of built-in bath having the usual foot end 2 with the water inlet 3 and the waste 4, the head of the rim 5 has a series of buttons 6 secured thereto by drilling and threading small holes in the bath and securing the but-

tons therein. These may be coated with enamel. The handles for controlling the water may be mounted on the foot end 2 or above the top of the bath as my appliance is designed to suit substantially any standard type of bath installation.

A spring roller 7 which may be of any standard design is secured in a canopy 8 which is shown mounted on the wall 9 or on part of the bath structure if such extends upwardly. The canopy is closed at opposite ends 10 by end walls which form the mounting for the spring roller. The apron 11 of the canopy is slightly spaced from the upper surface 12 of the rim of the bath so that a water-proof sheet 13 of rubberized fabric may be drawn out from the canopy to cover the bath. A series of eyelets 14 of the usual type are secured to the edge of the sheet and are properly positioned to engage the buttons 6 on the end and sides of the bath.

The sheet is provided with a neck opening 15 having preferably secured at the edge thereof a rim of resilient rubber sheeting to form a tight fit indicated by the numeral 16. A slit 17 is formed in the sheet and preferably extends to the side of the bath so that it may be turned completely back to allow a person to step in the bath, sit down, and then clamp the overlapping edges by dome buttons 18, or the like. These may be readily fastened after a person is in the bath as the fabric is sufficiently flexible for a person to pinch the fasteners together.

For use with baths having the faucet handles above the rim I provide a pair of slits 19 with sufficient over-lap of the material so that the hands may be extended through the openings to manipulate the handles. These may afterwards be closed with dome or similar buttons 20.

The manner of utilizing my steaming appliance of Figures 1 and 2 may be substantially as follows: The person using the steam bath may extend the sheet covering as above described and then after sitting in the bath buttoning the covering snugly around the neck, or a person may first sit in the bath and then pull the covering over and around them, and after securing the head end and the sides buttoning the neck opening into snug position. The manner of steaming one's self would be obvious, that is, either a person may flow hot water into the bath at as high a temperature as they can stand, or

the waste pipe 4 may be left open and the hot water allowed to run out of the bath with a dam formed by a towel and thus allow the steam from scalding water to fill the bath.

In the construction shown in Figures 3 and 4 the covering sheet 21 is formed of a large piece of impervious or rubberized fabric and has a series of vacuum cups 22 secured by studs 23 with a separator 24 spacing the vacuum cup from the fabric. The sides and ends 25 of the sheet are preferably sufficiently long to drape over the rim of the bath and hang down the sides.

The appliance of Figures 3 and 4 would have a neck opening and hand slots similar to the construction of Figures 1 and 2. With this arrangement a person may either secure the covering to the rim of the bath

before entering the bath or they may secure it in position after they enter the bath. The separator 24 allowing their fingers to grip the vacuum cups and force them into close contact with the rim of the bath. It is preferable to have the sheet rather loose so that a person may move around in the bath to a certain extent and may occupy different positions from substantially lying down to sitting up straight.

It is obvious that the covering may be considerably modified in construction and manner of fastening to a bath in order to conform to the great variety of bath structures now in use. Moreover with the rolling type of covering it may be secured at either

end of the bath and pulled out to the other end, fastening at the end and sides or only at the end. A pleasing installation is to secure the roller to the side of the bath for a built-in bath installation and to have a long roller substantially the length of the bath with a wide sheet which may be drawn out to attach to the opposite side of the bath and to the ends. Other changes in design will be more or less obvious.

Having described my invention, what I claim is:

1. A steaming appliance for a bath comprising in combination a bath tub and covering sheet, a housing at one end of the bath to contain the sheet, means to secure the edges of the sheet to the rim of a bath, said sheet having an opening therein adapted to fit snugly around a person's neck.

2. A steaming appliance for a bath comprising in combination a bath tub, a roller secured at one end or side of the bath tub, a sheet of fabric wound on said roller, means to clamp the edges of the sheet to the rim of the bath tub, said sheet having an opening therein adapted to be secured snugly around a person's neck, said roller being of the spring type adapted to wind in the sheet, and a canopy enclosing the roller, the sheet having eyelets positioned on its edges adapted to be secured to buttons on the rim of the bath tub.

In testimony whereof I affix my signature.

ERIK LANDER.
